UNITED STATES PATENT OFFICE.

HENRY HORAN, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,486, dated September 20, 1881.

Application filed August 9, 1881. Term of patent 3½ years.

To all whom it may concern:

Be it known that I, HENRY HORAN, of East Orange, in the county of Essex and State of New Jersey, have invented a new and original 5 Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The figure A consists of open roses and 15 smaller circular flowers surrounded by leaves somewhat resembling those of the geranium, and having a branch of fern projecting from one portion. From the figure A extends the branch c, with leaves and circular flowers 20 thereon; also the branches a and b growing out of one stem and bearing leaves and circular flowers. The branch h projects from the figure A, bearing on it circular flowers and leaves, and runs obliquely across the design, 25 having smaller twigs or branches projecting from it in turn. The figures g and d are leafy branches projecting from A. The branch e also projects and bears circular flowers and a cross-shaped leaf.

The figure m is a vine, which starts near the 30 lower part of the figure A, to the right of branch g, and which, after running some distance downward toward branch d, is forked, its branches bending sharply upward, as shown at the right of the photograph. This vine m 35 bears rosette-like flowers and pointed leaves.

The figure B is a vine bearing several distinct leafy clusters upon it. The effect of the design is that of a central group of flowers and leaves, around which grow the leafy and flowing vines and branches already described.

I claim—

1. The design for carpets, consisting of the figure A and its branches a b c d e g h, substantially as shown.

2. The design for carpets, consisting of the figures B, substantially as shown.

3. The design for carpets, consisting of the figure m, substantially as shown.

4. The design for carpets, consisting of the 50 figures A, a, b, c, d, e, g, h, m, and B, substantially as shown.

HENRY HORAN.
